DESIGN FOR A TEXTILE FABRIC

Fania Lubitsch, New York, N. Y.

Application June 20, 1939, Serial No. 85,590

Term of patent 3½ years

To all whom it may concern:

Be it known that I, Fania Lubitsch, a citizen of the United States of America, residing at New York, city, county, and State of New York, have invented a new, original, and ornamental Design for a Textile Fabric, of which the following is a specification, reference being had to the accompanying drawing, forming part thereof, wherein the figure is a plan view of a piece of textile fabric embodying my design.

I claim:

The ornamental design for a textile fabric, substantially as shown.

FANIA LUBITSCH.
